UNITED STATES PATENT OFFICE.

JOSEPH FREDRICK WRIGHT, OF CINCINNATI, OHIO.

MUFF.

1,300,088.

Specification of Letters Patent.

Patented Apr. 8, 1919.

Application filed May 23, 1918. Serial No. 236,166.

To all whom it may concern:

Be it known that I, JOSEPH F. WRIGHT, a citizen of the United States, residing at Cincinnati, in the county of Hamilton and State of Ohio, have invented a new and Improved Muff, of which the following is a specification.

This invention has reference to that style of muff in which the body is of an undulating shape, that is the upper part or edge is curved on an arc of much less diameter than that on which the lower edge is curved and my said invention has for its object to provide an improved construction of muff of the general style stated in which is included a new form of side extensions that are especially adapted to serve as wrist warmers and for receiving the hands and lower parts of the arms while the latter hang from the body in the natural position.

Another object of my invention is to provide an improved construction of muff of the kind mentioned, of a simple and economical form and which is especially well adapted for children's uses and with side wings or "wristlets" extensions so projected from the body proper that cords or ribbons for hanging the muff from the neck may be readily and securely attached to or around the said side extensions.

With the above objects in view, my invention consists in the peculiar construction of muff hereinafter explained in detail, specifically pointed out in the appended claim and illustrated in the accompanying drawings, in which:

Figure 1 is a perspective view of my improved muff.

Fig. 2 is a diagrammatic plan view that illustrates the back and front or pattern members.

Fig. 3 is a diagrammatic plan view that illustrates a slightly modified form of the pattern members hereinafter specifically referred to.

In carrying out my invention, I form the muff body of two like pieces or pattern members 1-2 that constitute the back and front members of the muff, and while I have not so shown it, in making up the complete muff, the lining pieces are cut on the same pattern or shape.

Each of the sections 1-2, in my construction of muff, are shaped as diagrammatically shown in Fig. 2, by reference to which it will be observed the sections each include

a body *a* that embraces all of the pattern within the upper restricted concaved edge 3, the lower convexed edge 4, and the opposite ends indicated by the dotted lines 5-5 that 60 extend from the terminals 40-40 of the bottom edge and the ends 30-30 of the upper concaved edge 3, as is clearly shown in Fig. 2.

At the upper opposite edges, the pattern pieces include lateral or wing-like extensions 65 6-6 of substantially triangular shape, whereby to provide restricted throat-like openings 7-7 that project substantially vertical to the body and thereby provide for inserting the hands and the lower portions of 70 the arms into the muff, while hanging in the natural position from the body, in distinction to bending the fore-arms toward each other, as is necessary when using the conventional style of muff.

An improved advantage in forming each of the pattern pieces 1-2 with the triangular wing-like extensions 6 is that the said extensions 6-6 constitute wrist warmers, as they provide for a close fitting about the 80 wrist when the hands are inserted partly into the muff, thereby providing for the desired use of the hands and the wrist without restricting the use of the muff for carrying the articles such as are usually held therein. 85

By forming the extensions 6 as shown and described, they provide for convenient points for attaching a hanger cord or ribbon 8, as is clearly shown in Fig. 1 and, by reason of the abrupt joining of the edges 60-60 of 90 the extensions with the lower curved edges 40-40 of the body, after the wrists have been inserted into the wristlet portions, any movement or bending of the hands or the wrists tends to cause the muff body to buckle 95 or crease inwardly in the direction indicated by the arrows *x-x* on Fig. 2 and thereby causes the said wristlet portions to the more tightly bind about the wrists and avoid any tendency of the side openings to spread. 100

While the curved design of the upper edge indicates a preferred shape for the smaller sizes of muffs, for the larger sizes of muffs the said upper edge may be shaped as shown in Fig. 3, and when thus made greater 105 elongation of the extensions 6-6 is provided.

When the upper edge is formed, as indicated by the full line *c-c*, as shown in Fig. 3, the junction of the edges 60 and the curved edges 40 are made more abrupt, as indicated by 60^a-60^a. 110

What I claim is:

A muff comprising a body portion whose opposite open ends terminate in triangular extensions, the said extensions forming 5 wristlet portions whose passageways extend substantially vertically, the openings to the said passageways extending substantially horizontally, the meeting edges of the tri-

angular portions and the lower edge of the body portion being abruptly joined, where- 10 by the muff, at such points of connection, tends to buckle or bend inwardly to bind tightly on the wrists of the user, when moving the hands or wrists held within the muff openings.

JOSEPH FREDRICK WRIGHT.
